ARTHUR E. GLASSMANN AND JULIUS BARTHA, OF NEW YORK, N. Y.

SPARK-PLUG.

1,359,358.

Specification of Letters Patent. Patented Nov. 16, 1920.

Application filed March 18, 1920. Serial No. 366,874.

To all whom it may concern:

Be it known that we, ARTHUR E. GLASSMANN, a citizen of the United States, and JULIUS BARTHA, a citizen of Hungary, and both residing at the city of New York, in the county of New York and State of New York, have invented certain new and useful Improvements in Spark-Plugs, of which the following is a specification.

- 10 Our invention relates to improvements in spark plugs and the object of our invention is to provide a simple, convenient and efficient spark plug for use in internal combustion engines; a further object of our invention is to provide a spark plug having a plurality of spark gaps; a further object of our invention is to provide a spark plug in which the spark gap is provided with a plurality of steps whereby the fouling of 20 the gap by carbon deposits will be minimized; a further object of our invention is to provide a spark plug, having a plurality of auxiliary spark gaps, and a further object of our invention is to provide a spark plug in which the adjustment of the spark gap is eliminated and in which a minimum current will operate efficiently.

We accomplish these objects by the device illustrated in the accompanying drawings 30 in which—

Figure 1 is a view of the spark plug in elevation;

Fig. 2 is a vertical section of the same;

Fig. 3 is a detail of the ignition dome 35 with the rings in position and cut away at the front; and

Fig. 4 is a section of the same on the line 4—4 in Fig. 3.

Similar characters refer to similar parts 40 throughout the several views.

Referring to the drawings, we provide a hollow body or core of lava, porcelain or other suitable insulating material which is preferably constructed of a plurality of 45 cylindrical integral sections 1, 2, 3 and 4 of progressively increased diameter, a shoulder 5 and a terminal dome 6 in which are cut or otherwise formed a plurality of annular seats 7, 8, 9, 10 and 11 and a plurality 50 of longitudinal grooves or spark gaps 12, 13, 14 and 15 intersecting the said annular seats.

The core is incased at its lower end section and adjacent its dome 6 by an exteriorly 55 screw threaded shell 16 for attachment of the plug to the engine and which is pro-

vided interiorly with steps 17, 18 and 19 to engage the shoulders of the sections 2, 3 and 4 respectively of the core and having a lip 20 adapted to be bent over upon the shoulder 5 of the core to securely lock or bind the shell 16 upon the core.

Over the top end section 1 of the core is provided an insulating cap 21 which rests upon the shell 16 and is preferably locked thereon by bending over a lip 22 of the shell 16 and also by means of a lock nut as hereinafter explained.

Within the core is provided a terminal 23 having an enlarged head 24 extending through the dome 6 and having an upper end section 25 screw threaded to form a binding post, with a suitable washer 26 and nut 27, and also to receive a washer 28 and lock nut 29 to bind the parts together. Upon the dome 6 of the core and in the seats 7, 8, 9, 10 and 11 thereof are provided suitable rings 28, 29, 30, 31 and 32 to form steps for the spark between the terminal head 24 and the shell 16.

These rings or steps are separated from each other and from the head 24 and shell 16 by walls or partitions 33, 34, 35, 36 and 38, being the sections of the dome 6 lying intermediate the cut out seats 7, 8, 9, 10 and 11, which walls or partitions are broken away by the longitudinal spark gaps or grooves 12, 13, 14 and 15.

The device being thus assembled with the shell 16 grounded to the engine and the electric current transmitted by a suitable lead wire to the terminal 23 by means of the binding post thereon, a plural spark gap will be formed between the terminal head 24 and the shell 16 through the grooves or gaps 12, 13, 14 and 15 with intermediate connecting steps formed by the rings 28, 29, 30, 31 and 32. The circuit is from the lead wire terminal across the gaps 12, 13, 14 and 15 in the dome to the metal shell 16 seated in the engine forming a plurality of operative ignition sparks between the terminals and as will be apparent a minimum efficient current is thus required and the fouling by carbon deposits of any number of these spark gaps so long as continuous passage remains through any combination of the gaps, 12, 13, 14 and 15 and the intermediate steps, will not destroy the operativeness of the device and the spark of the gaps thus formed and the attendant explosion will tend to burn off or remove

the carbon deposits which may form at the remaining gaps.

Having thus described our invention, what we claim is:

5 1. In a spark plug the combination of a plurality of terminals, a spark gap between the terminals, a plurality of intermediate steps between the terminals and a plurality of partitions between said steps provided
10 with gaps therein to permit the passage of operative sparks between the terminals and the said steps.

2. In a spark plug, the combination of a hollow insulating core, a terminal therein, 15 and projecting beyond the ends of the core, an end section on the core having a plurality of seats divided by partitions, spark gaps in said partitions, steps for the electric current in said seats and a shell on said core 20 whereby an electric current passed from the

said terminal to the said shell will form sparks through the gaps in the said partitions.

3. In a device of the character described, the combination of an insulating core, a 25 shell thereon adapted to be grounded to an engine, an electric terminal projecting beyond said core, a spark gap between said terminal and said shell and a plurality of steps in said spark gap, partitions between 30 said steps and having a plurality of gaps whereby the current from the terminal to the shell will be caused to pass through the steps and form operative sparks intermediate said steps.

In testimony whereof we affix our signatures.

ARTHUR E. GLASSMANN.
JULIUS BARTHA.
